Primary Examiner — Paula Allen Greene(74) *Attorney, Agent, or Firm* — Cantor Colburn LLP(57) **CLAIM**

The ornamental design for an artificial intelligence speaker, as shown and described.

DESCRIPTION

FIG. 1 is a front perspective view of an artificial intelligence speaker, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is an enlarged view of the encircled portion 9 in FIG. 6;

FIG. 10 is an enlarged view of the encircled portion 10 in FIG. 7; and,

FIG. 11 is an enlarged view of the encircled portion 11 in FIG. 8.

The even-dash broken lines illustrating portions of the artificial intelligence speaker form no part of the claimed design. The dot-dash broken lines encircling enlargement portions of the artificial intelligence speaker form no part of the claimed design.
